TWISTING AND WINDING OF TEXTILE FIBERS

Edward C. Pfeffer, Jr., and John J. Gannon, Troy,
and John J. Fiscella, Menands, N. Y., assignors
to Cluett, Peabody and Company, Inc., Troy,
N. Y., a corporation of New York

Application July 1, 1948, Serial No. 36,476

3 Claims. (Cl. 57—58)

1

This invention relates to the winding and twisting of bundles of textile fibers of relatively long lengths, and particularly to an improved method and apparatus for twisting a bundle or group of fibers and winding them into a package on a bobbin, and which may when desired, be included in the same handling operation as the drawing of staple fibers.

One object of the invention is to generally improve and simplify twisting and winding apparatus and methods for textile fibers.

Another object of the invention is to provide an improved method and apparatus for twisting and winding yarns, groups of filaments, and/or long bundles of textile fibers on a bobbin to form a package; which enables the winding of either large, medium or small packages with the same efficiency and effectiveness; with which thread, filaments, yarns or bundles of fibers may be wound in progressive turns and superposed layers on a bobbin with a desired degree of tautness; with which the winding may take place for relatively long periods with a minimum of attention from an operator or attendant; with which breakage of the threads, filaments, yarns or fibers being wound on the bobbin will be a minimum; and with which rapid rotation of the bobbins in the event of mechanical trouble will be automatically prevented.

Another object of the invention is to provide an improved method and apparatus for imparting about a two for one twist to a yarn, thread, bundle of textile fibers or filaments, in a rapid continuous operation and handling; also for winding the twisted yarns, threads, filaments or fibers on a bobbin to form a package; which will handle the filaments or fibers by twisting or winding them at least as rapidly as by any previous methods and apparatus for twisting and winding textile materials; with which the fibers or filaments being wound on the bobbin may be wound in helical form and superposed layers, or as frusto-conical superposed layers that have a somewhat telescoping or nesting relation to each other, and which layers progress in a direction from end to end of the bobbin.

Another object of the invention is to provide improved apparatus for accomplishing each of these objects, and which will be relatively small, compact, durable, convenient, inexpensive, and of relatively large capacity.

Other objects and advantages will be apparent from the following description of one embodiment of the invention, and the novel features thereof will be particularly pointed out herein-
after in connection with the appended claims.

2

In the accompanying drawings:

Fig. 1 is a side elevation, partly in section and partly schematic, of apparatus constructed in accordance with this invention and useful in practicing the method;

Fig. 2 is a vertical central, elevation of part of the twisting and winding mechanism of the same;

Fig. 3 is a similar elevation on a larger scale 10 of a part of the mechanism shown in Fig. 2;

Fig. 4 is a plan of the mechanism shown in Fig. 2, but with the winding member and the bobbin removed from the spindle.

Fig. 5 is a plan of part of the mechanism of 15 Fig. 4 but with the safety stop in a different or operative position; and

Fig. 6 is a side elevation of the parts shown in Fig. 4, but partly in section in order to show details of construction.

20 In the illustrated embodiment of the invention, and referring first particularly to Fig. 1, the invention is illustrated, by way of example, as part of a mechanism for drawing rovings of staple fibers to form a twisted yarn and winding 25 the yarn on a bobbin. For this purpose the drawing mechanism is of a suitable roller type, designated generally at 1, which is mounted on a roll stand 2 on a roll beam 3. The beam frame 3 is provided on a suitable main frame 4. A 30 creel or bobbin stand 5, is mounted on the upper part of the frame 4, and rotatably supports a plurality of vertically disposed bobbins 6, on which are wound the rovings 7 and 8 of staple fibers, which are to be drawn and combined into 35 a yarn 9 and then twisted and wound on a bobbin, to form a package. The rovings 7 and 8 are unwound from the bobbins 6 and passed together, side by side, through the roller drawing device 1, where they are combined and drawn 40 into a yarn 9, which operation frequently is called spinning from double roving. Any number of rovings may be combined in this manner to make each strand of yarn. The roller drawing device 1 is provided with consecutively arranged pairs 45 of rollers operating at progressively higher speeds, and the rovings pass between the rollers of each pair in succession.

The drawn, combined rovings are conducted as a yarn 9 through a guide or eye 10 carried on a rod 11 projecting from the roll beam 3. This is a typical drawing mechanism in common use, and it has, therefore, been illustrated only rather schematically, since any suitable drawing mechanism may be employed. The drawing rollers are driven by a suitable mechanism (not shown) 55 in the proper speed ratios for the successive pairs,

with power for driving them obtained from a gear 12 coupled to one of the drawing rollers. The gear 12 meshes with and is driven by a gear 13 which in turn meshes with and is driven by a pinion 14.

The pinion 14 is coupled to a larger gear 15 concentric therewith which meshes with and is driven by a pinion 16 which is in turn concentric with and coupled to a gear 17 that meshes with a gear 18 fixed on the shaft 19. The gears and pinions 12 to 17 are suitably mounted for rotation, but since such driving mechanisms are old and the details thereof may vary considerably, this driving mechanism is shown rather schematically. The shaft 19 is driven from any suitable source of power (not shown) such as an electric motor, and this shaft through the driving connection represented schematically by the meshing gears 12 to 18, will drive the gear 12 at a lower rate than the shaft 19. Any other suitable speed reducing mechanism may be employed between the shaft 19 and the roller drawing mechanism 1.

Disposed a short distance below and aligned with the guide 10 is a twisting and winding device designated generally at 20. This device 20, shown in sectional elevation in Fig. 2, is mounted on a support or platform 21 so as to upstand therefrom. Disposed in a passage in the support 21 (Fig. 2) is a bearing member 22 with a flange 23 on its upper end which overlies the support 21. Adjacent to its upper and lower ends this member 22 is provided, in its interior, with vertically spaced and aligned anti-friction or ball bearings 24 and 25, which rotatably support a sleeve 26 that passes upwardly through the support 21 and the member 22. One of these bearings, such as the upper bearing 24, is a combined radial and thrust bearing, and its inner race engages against a downwardly facing shoulder 27 on sleeve 26 which supports the weight of the sleeve 26. The outer race of bearing 24 engages against a shoulder 28 provided in the passage or interior of the member 22, which holds the bearing in position and transfers the weight of the sleeve 26 to the member 22.

Above the flange 23 (Fig. 2) the sleeve 26 is provided with a peripheral flange 29 which supports a disc or plate 30 that has a central aperture telescoping over the sleeve 26. Disposed above the disc 30 and around the upper end of the sleeve 26 is a tubular member 31 which telescopes downwardly over the upper end of the sleeve 26 and in spaced relation thereto. This member 31 is part of a bobbin support and is rotatably supported on the upper end of the sleeve by vertically spaced, ball or anti-friction bearings 32 and 33. These bearings 32 and 33 are also combined radial and end thrust bearings, and the lower bearing 32 has its inner race resting on an external shoulder 34, facing upwardly, of the sleeve 26, a short distance from its upper end. The outer race of that bearing is counter-sunk into the chamber of the member 31 at its lower end, and seats against a shoulder 35 thereof. The outer race of the upper bearing 32 seats against a shoulder 36 within the chamber of the tubular member 31.

A lock nut 37 is threaded upon the periphery of the upper end of the sleeve 26, and overlies the upper bearing 32 so as to confine the member 31 to the sleeve 26, and a similar lock nut 38 is threaded upon the lower end of the sleeve 26, but some distance above its extreme lower end, and engages against the inner race of the

bearing 25. Fixed on the lower end of the sleeve 26 is a driving pulley 39 which is driven by a belt 40, which in turn is driven by a pulley 41, see Fig. 1, fixed on the main shaft 19.

5 Fixed upon the periphery of a reduced lower end of the member 31, (Fig. 2) is a plate or disc 42 which lies in close proximity to, but is spaced slightly above, the upper face of the disc 30. A spindle 43 passes upwardly through the 10 sleeve 26 and well above and below it, and is rotatable and slidable in the sleeve except as they are coupled for rotation together in a manner which will be hereinafter explained. The spindle 43 rises well above the member 31, and rotatably confined on this upper rising end of the 15 spindle is a tubular bobbin support 44 which is provided adjacent its lower end with a laterally extending flange 45 that rests upon the upper end of the member 31, to which it is secured, such as by screws 46, see Fig. 4. The flange 45 may have, depending from its lower face, an 20 annular ring 47 (Fig. 2) which telescopes within the open upper end of the member 31 and which serves to accurately locate the bobbin support 25 on the spindle, since the bobbin support does not closely fit the spindle but is preferably provided with substantial clearance from the upper end of the spindle.

The exterior of the bobbin support 44 is formed 30 to receive and detachably support a suitable bobbin 48 on which the thread, filaments, or fibers are to be wound, and preferably the exterior surface of the lower end of the bobbin support is upwardly tapered slightly as at 49, 35 and the bobbin preferably has a similarly tapered seat or socket that serves to locate and support it and provide a frictional drive between it and the bobbin support. The upper end of the spindle extends substantially above the upper end of the bobbin support 44, and telescoped 40 within this upper end of the spindle 43 is a tube 50 which is frictionally fitted to, although detachable from, the spindle. This tube 50 rises above the upper end of the spindle and there 45 mounts a cap 51 which telescopes over the upper end of the tube 50. The cap 51 is rotatably confined on the upper end of the tube 50 by a connection which is preferably of relatively low friction, such as vertically spaced ball bearings 52 and 53. The cap 51 is thus rotatably mounted, 50 by the ball bearings 52 and 53, on the upper end of the tube 50 that is frictionally coupled to the upper end of the spindle.

The cap 51 and the tube 50 are firmly coupled 55 through the bearings so that by lifting the cap, the tube 50 may be pulled from the spindle. The cap 51 is provided with a passage 54 at its upper end which is vertically aligned with, and forms a continuation of, the passage of the tube 50. Secured to the lower end of the cap 51 at its periphery is a sleeve 55 which telescopes downwardly over the upper end of the spindle and the upper end of the bobbin. Diametrically opposite and downwardly diverging rods 56 and 57 depend 60 from the lower end of the sleeve 55, and at their lower ends terminate in thread guides or eyes 58. A ring 59 surrounds the spindle and is secured to the lower ends of the rods 56 and 57 so as to form therein a unit, with the eyes 58 65 preferably below the ring 59. The diameter of the ring 59 is greater than the maximum expected diameter of the completed package on the bobbin.

The spindle 43 is provided with a passage 60 70 (Figs. 2 and 3) that extends downwardly from

the upper end of the spindle to a position well below the upper end of the sleeve 26, and, for a considerable length from its lower end, this passage 60 opens sidewise through the spindle to form a vertically elongated slot 61 in the portion sliding in the sleeve 26. The disc or plate 30 is provided with a thread passage 62 extending radially from the periphery of the disc to its central opening which telescopes over the sleeve 26. The wall of the sleeve 26 over which the plate 30 fits is provided with a passage 63 (Fig. 3) which is aligned with the thread passage 62 when the plate 30 is rotated on the sleeve 26 until the passages 62 and 63 are end to end, as shown in Fig. 3.

A sleeve or bushing 64 is disposed in this passage 63 and projects through slot 61 into the passage 60 of the spindle 43 and the projecting end has an enlarged passage 65 at that end. Disposed within the passage 60 in the spindle is a length of tubing 66, Figs. 2 and 3, open at its upper end. At its lower end it is turned or bent laterally as an elbow 67. The free end of the elbow has a periphery that telescopes within the enlarged passage 65 in the projecting part of the sleeve or bushing 64. The tube 66 slides along slot 61 and serves as a key which couples the sleeve 26 and spindle 43 for rotation together while the spindle is free to slide endwise through the sleeve. The tube 66 also serves as a continuation of the bushing or sleeve 64.

Counter-sunk into the lower face of the flange 42 are one or more permanent magnets 68, so that the outer faces of these magnets are close to but spaced slightly above the upper face of the disc or plate 30. Similar permanent magnets 69 are counter-sunk into the upper face of an annular member 70 which is secured on the upper face of the flange 23, and which surrounds a bushing 71 that rests upon the flange 23 and has an inturned flange that bears upon the upper end of the outer race of bearing 24. The magnets 69 are disposed immediately below the magnets 68 and as close as possible to the under face of the disc 30. These magnets 68 and 69 are permanent magnets and are disposed in similar, vertically aligned pairs at spaced intervals about the spindle axis. The correspondingly positioned ends of each pair of magnets 68 and 69 so that the north pole of each magnet 68 will be close to and above a south pole of magnet 69 of that pair. This provides a strong magnetic attraction between the pairs of superposed magnets, and since the annular member 70 is secured to the flange 23 against rotation about the spindle, this magnetic attraction between the magnets 68 and 69 will yieldingly hold the member 31, and the bobbin support 44 of which it is a part, against rotation with the sleeve 26 and the spindle 43.

The lower end of the spindle 43 (Fig. 1) is rotatably mounted in a combined radial and thrust bearing 72 carried in a small casing 73, and thus by moving the casing 73 vertically back and forth one may elevate and lower the spindle. The lower end of this casing rides on a roller 74 which is rotatably carried on a pin 75 extending laterally from a lever 76 that is pivoted on a frame 4 by a pivot pin 77. Intermediate of its ends the lever 76 carries another laterally extending pin 78 which rotatably mounts a roller cam follower 79, and the latter rides on the periphery of a cam 80, which is fixed on a shaft 81. This shaft also has fixed thereon a worm wheel 82. Meshed with the wheel 82 for driving it is a worm screw 75

83 fixed on the end of a shaft 84, which is rotatably mounted in the frame 4. The shaft 84, on one end, carries a beveled gear 85 which meshes with and is driven by a bevel gear 86 that is attached to and is driven by a sprocket wheel 87. The wheel 87 is driven by sprocket chain 88 from a sprocket wheel 89 which is coupled to and driven from the gear 13.

It will thus be observed that the cam 80 will be driven at a relatively slow speed in synchronized relation to the operation of the drawing rolls, and as the cam 80 rotates it will act through the lever 76 to raise and lower the spindle 43. The weight of the spindle and the housing

15 73 is usually sufficient to lower the spindle when the lever 76 is lowered by the cam 80, but suitable means may be provided for urging the spindle downwardly so as to keep the housing 73 in contact with the roller 74 at all times. As a suitable example of each urging mechanism, the housing 73 may be provided with diametrically disposed lugs 90 and links 91 depending from the lugs 90 carry a cross bar 92 from which a weight 93 is suspended by a ring 94.

20 25 Referring now particularly to Figs. 4 to 6, the flange 23 and the annular member 70 are provided with a notch on one side, and in this notch is disposed a bell crank lever 95 mounted on a pivot pin 96 of a bearing boss 97 attached to the upper face of the flange 23 to which it is secured, such as by screws 97A. One arm 98 of the lever 95 mounts in its upper face one of the permanent magnets 69, see Fig. 6, and the support 21 below lever 95 with a recess 99 into which the lower arm 98 may swing by gravity when the magnetic pull ceases on that particular magnet 69 which is carried by the lever 95. The bell crank lever is held normally in its full line position shown in Figs. 4 and 6 by the magnetic 30 35 attraction between its magnet 69 and the permanent magnet 68 immediately above it.

When the bell crank lever 95 is in its full line position shown in Fig. 6, a nose 100 on the upper end of the other arm of that lever will be held away from the disc or plate 30, but if the bobbin support and its flange 42 should start to rotate a magnet 68 will move from its position above the magnet 69 on the arm 95, and when this occurs the magnetic attraction on the magnet 69 carried by the lower end of the bell crank lever is relieved and that lever will at once rotate into the dash line position shown in Fig. 6 and full line position shown in Fig. 5, which will carry the nose 100 into a position above the upper face of the plate or disc 30 and against the periphery of the flange 42. The periphery of this flange 42 is provided with notches 101 and 102 so as to provide shoulders 103 at the ends of the notches. When the nose 100 is in the dash line position shown in Fig. 6, which is the full line position shown in Fig. 5, the nose 100 will be in the path of travel of the shoulders 103, and the engagement of a shoulder 103 sidewise against the nose 100 of the lever 95 will positively prevent further rotation of the member 31 and the bobbin support 44.

In the operation of the illustrated mechanism, and assuming that the parts are assembled and connected as shown in the drawings, the yarn 9 from the drawing rolls 1 will pass through the guide eye 10 to the outer end of the thread passage 62 in the disc or plate 30, and then conducted along that passage and through the sleeve or bushing 64 into the elbow 67 of the tube 66, then upwardly through tube 66 into and along

the passage 60 of the spindle, then into and along the passage of the tube 58 and through the opening 54 of the upper end of the cap 51. The yarn or thread then passes over the side of the cap 51 as shown in Fig. 1, downwardly past the ring 52, to one of the eyes 58, then through that eye and to the bobbin to which it is attached. The thread may be easily threaded through the passages in the plate 30 and the spindle and other similar passages, by first inserting an end of the 10 thread into one end of the passage through which it is to be passed and then blowing a jet of air along the passage from that same end, which will carry the thread through the passage and out of the top of the cap 51.

With the parts arranged in this manner, and with the yarn 9 threaded through the twisting and winding mechanism in this manner one moves the bobbin on its support until one of the magnets 69 is directly above the bell crank lever, 20 and the bell crank lever 95 is then moved into its full line position shown in Figs. 4 to 6, whereupon the magnet 69 on that lever will be close to the under face of the plate 30. The magnetic pull between those magnets will hold the bell 25 crank lever 95 in this full line position determined by engagement of the upstanding arm of the lever with the end of the slot of this bearing in which it is mounted, and the magnetic pull between the magnets of the superposed pairs, will prevent rotation with sleeve 26 of the flange 42 of the member 31, and the bobbin support. There will be sufficient friction in the bearings 52 and 53 of the cap 51 to cause, when the spindle is 30 rotated, a rotary torque on the cap 51 in the same direction as the rotation of the spindle. This rotary torque will tend to rotate the eyes 58 which are supported below the cap and thus carry the yarn or thread around the bobbin as rapidly as it is released by the drawing rolls, twisted and 35 conducted from the cap 51 to one of the eyes 58.

When the shaft 19 is driven from the motor or other source of power, the drawing rolls will be operated to draw and combine the rovings 7 and 8 into the yarn 9, and the yarn 9 will thus be fed continuously through the eye or guide 10 which is axially aligned above the upper end of the spindle. The yarn 9 then passes downwardly to the outer end of the thread passage 62 in the plate 30, then upwardly through the spindle and bobbin, over the cap 51, downwardly through a thread guide or eye 58, and then is wound on the bobbin. At the same time the shaft 19 rotates the sleeve 26 at a relatively high speed compared to the speed of the drawing rolls, and also rotates the cam 80 at a relatively much lower rate. The sleeve 26 rotates the spindle 43 because of the sliding coupling between the two through the sleeve or bushing 64, and, as the spindle rotates, the cam 80 slowly raises and lowers the spindle in a manner to wind the thread, 40 yarn or bundle of fibers on the bobbin in progressive turns and in superposed layers.

The yarn 9 passes downwardly to the winding device 20, is rotated about the axis of the spindle 43 to form a balloon, and the bobbin and winding mechanism are within this balloon. This provides a two for one twist of the yarn or fibers 9, and the yarn 9 is wound on the bobbin as rapidly as it passes upwardly through the spindle. As the spindle rises and falls so will the cap 51, the sleeve 55, the arms 56 and 57, and the thread guide eyes 58. The friction in the bearings in the cap 51 provides sufficient turning torque on the cap from the spindle to exert a slight pull on 50 the cap.

the yarn 9, wind it on the bobbin and pull the yarn through the sprindle. The amount of friction in the rotatable mounting of the cap 51 on the spindle determines the turning torque on the yarn 9.

The bobbin is held stationary during this time, but if dirt should get in the bearings supporting the bobbin support, and the bobbin should start to turn, immediately the magnet 69 which is over the safety lever 95 will begin to move, the magnetic pull on the magnet 69 beneath it will decrease, whereupon the lever 95 will rock into the dash line position of Fig. 6 and the full line position of Fig. 5, so as to position the nose 100 in the path of a shoulder 104 of the peripheral flange 42. This will immediately stop further rotation of the bobbin. The bell crank lever engages against a shoulder 104 of the support therefor, which limits the upward movement of the arm 98 and the magnet 69 to the position shown in full lines in Fig. 6. A stop 105 in one of the walls of the recess 90 is engaged by the arm 98 when the bell crank lever turns into the dash line position of Fig. 6, and prevents the nose from bearing or riding on the disc 30, but holds it in the path of a shoulder 103.

In the absence of a generic term, the expression "bundle of textile fibers" is intended to include within its scope, yarns and rovings of textile fibers, threads, strands, and groups of filaments brought together side by side to form a thread or yarn. The twisting and winding apparatus is useful for the twisting and winding of any of such yarns, rovings, threads, groups of filaments and bundles of fibers, but when such mechanism is employed with drawing rolls, as shown, then, of course, the expression "bundle of textile fibers" is intended to refer only to staple fibers in the form of yarns or rovings.

It will be obvious that various changes in the details, materials, and arrangement of parts, which have been herein described and illustrated in order to explain the nature of the invention, may be made by those skilled in the art within the principle and scope of the invention as expressed in the appended claims.

We claim:

1. In a winding and twisting device, the combination of a main support, an upstanding sleeve carried by said support for rotation about its longitudinal axis, a spindle passing through and slidable endwise in said sleeve and having a threaded passage from its open upper end to the portion within said sleeve, a disc-like member telescoped over said sleeve and having a thread passage from its outer periphery to its aperture receiving said sleeve, said sleeve having a thread passage aligned with the thread passage of said disc and extending to the passage of the sleeve, said sleeve and spindle having a sliding coupling by which the spindle rotates with the sleeve and is also slidable within the sleeve during such rotation, a bobbin support rotatably mounted on said sleeve above said disc and having at its lower end a flange extending close to but slightly spaced from the upper face of said disc, a permanent magnet mounted on the underface of said flange, a lever pivoted on said support outwardly beyond the outer periphery of said disc, one arm 60 of the lever extending beneath said member and carrying a permanent magnet disposed beneath and directly opposite the permanent magnet of said bobbin support and free to drop when magnetic attraction ceases, the other arm of said 65 support having a nose movable against said bob-

bin support when the lever rocks in a direction to carry its said permanent magnet away from said member, said bobbin support having a shoulder engageable by said nose when the nose moves against the bobbin support for stopping rotation of said bobbin support with the sleeve when the magnet on the bobbin support is out of magnetic attraction with said lever-carried magnet.

2. A device for twisting a long, slender bundle of textile fibers and winding the twisted bundle on a bobbin or form, which comprises a bobbin support having an opening from end to end and formed on its exterior periphery to receive and hold a bobbin telescoped thereover, and mounted for rotation about the longitudinal axis of said opening, a member sliding endwise through, and rotating in said opening, and having a passage extending longitudinally thereof from an open end thereof, and intermediate of its ends and outside of said support having an outwardly opening conduit rotating therewith, means for guiding said bundle endwise from beyond said open end of said member, past said support and into said conduit, for movement endwise into and along said passage to the open end thereof, a winding element rotatably mounted on the open end of said member, movable endwise with said member and carrying a thread guide at one side of said bobbin support for guiding the bundle from the open end of said member to a bobbin on said support, means for rotating said member while it is free to move endwise, means for causing movement of said member back and forth endwise during its rotation, magnetic means partly stationary and partly carried by said bobbin support, with an air gap between them through which said bundle may move, in rotation, between said guiding means and said member, for holding said bobbin support from rotation about said axis, a safety stop yieldingly urged into a position to positively stop rotation of said bobbin support, and magnetic means carried partly by said bobbin support and partly by said stop, for magnetically holding said stop in non-stopping position, and releasing said stop automatically by rotary movement of said bobbin support.

3. A device for twisting a long, slender bundle of textile fibers and winding the twisted bundle on a bobbin or form, which comprises a bobbin support having an opening from end to end and formed on its exterior periphery to receive and hold a bobbin telescoped thereover, and mounted for rotation about the longitudinal axis of said opening, a member sliding endwise through, and rotating in said opening, and having a passage extending longitudinally thereof from an open end thereof, and intermediate of its ends and outside of said support having an outwardly opening conduit rotating therewith, means for guiding said bundle endwise from beyond said open end of said member, past said support and into said conduit, for movement endwise into and along said passage to the open end thereof, a winding element rotatably mounted on the open end of said member, movable endwise with said member and carrying a thread guide at one side of said bobbin support for guiding the bundle from the open end of said member to a bobbin on said support, means for rotating said member while it is free to move endwise, means for causing movement of said member back and forth endwise during its rotation, magnetic means partly stationary and partly carried by said bobbin support, with an air gap between them through which said bundle may move, in rotation, between said guiding means and said member, for holding said bobbin support from rotation about said axis, a safety stop yieldingly urged into a position to positively stop rotation of said bobbin support, and magnetic means carried partly by said bobbin support and partly by said stop, for magnetically holding said stop in non-stopping position, and releasing said stop automatically by rotary movement of said bobbin support.

50

support having an opening from end to end and formed on its exterior periphery to receive and hold a bobbin telescoped thereover, and mounted for rotation about the longitudinal axis of said opening, a member sliding endwise through, and rotating in said opening, and having a passage extending longitudinally thereof from an open end thereof, and intermediate of its ends and outside of said support having an outwardly opening conduit rotating therewith, means for guiding said bundle endwise from beyond said open end of said member, past said support and into said conduit, for movement endwise into and along said passage to the open end thereof, a winding element rotatably mounted on the open end of said member, movable endwise with said member and carrying a thread guide at one side of said bobbin support for guiding the bundle from the open end of said member to a bobbin on said support, means for rotating said member while it is free to move endwise, means for causing movement of said member back and forth endwise during its rotation, a magnetic holding unit having one part carried by said bobbin support, a stop element mounted for movement into and out of a position in which it positively stops rotation of said bobbin support, and yieldingly urged into said position, another part of said unit carried by said stop element and effective by the magnetic pull between the parts, when said stop element is out of said position, to hold said stop element out of said position.
